LIGHT REFLECTING SIGN

Edward H. Branson, Rochester, N. Y., assignor to
General Railway Signal Company, Rochester,
N. Y.

Application June 2, 1933, Serial No. 674,053

4 Claims. (Cl. 88—82)

This invention relates to improvements in luminous signs, and more particularly to signs of the type which are rendered luminous by reflection from an external source of light.

In protecting highway traffic crossing railway tracks, it is often necessary to provide a sign along the highway such as for displaying information concerning the number of tracks to be crossed. It then becomes desirable to illuminate such signs by a means which is entirely dependable as well as economical in maintenance and operation.

In view of the above and other considerations, it is proposed in accordance with the present invention to provide a sign which is rendered luminous by an improved form of cataphotes or light reflecting buttons arranged in the sign so as to reflect light directed thereon by automobile head lamps and the like. It is proposed to provide such a light reflecting button which is substantially indestructible and impervious to the entrance of moisture or other foreign material. It is further proposed to construct a reflector button which is a unit structure adapted for convenient installation in such signs so that perfect alignment of reflecting surfaces is assured.

Other objects, purposes and characteristic features of the present invention will appear as the description thereof progresses, during which, references will be made to the accompanying drawing which shows the invention in a manner to make it easily understood rather than with a view of showing the particular construction preferably employed in practice, and in which:—

Fig. 1 shows a typical application of a sign constructed in accordance with the present invention.

Fig. 2 is a plan sectional view of a detail of the present invention.

Fig. 3 is a plan sectional view of a modified form of the detail shown in Fig. 2 also constructed in accordance with the present invention.

Fig. 4 is a partial front elevational view of the present invention with parts removed to more clearly show its construction.

Fig. 5 is a plan section of Fig. 4 taken on line 5—5 and viewed in the direction indicated by the arrows.

In the accompanying drawing, the present sign is shown as formed on a metal background B by attaching hollow metal characters thereto such as the letters "T" and "R" shown in Fig. 4. These characters may be secured to the background B by rivets 6 passing through the back-

ground B and through thin lugs 7 which may be integral with the hollow characters. The characters of the sign are preferably painted to contrast with the color of the background B for good daytime observation of the sign, such as for example, the characters may be white and the background B and lugs 7 may be black.

The faces of the characters have a series of holes 8 therein to form the general outline of each character in the manner shown in the letter "R" of Fig. 4. These holes 8 may be threaded to receive a threaded portion of one form of reflector buttons L in the manner shown in the letters "T" in Fig. 4 and Fig. 5.

It is contemplated that the reflector buttons L may be constructed in either of the two general forms shown herein, the form shown in Fig. 2 comprising a general cup-shaped metal reflector unit 9 with a light transmitting material 10 molded therein. The inside of the back of the reflector unit 9 is a concave polished or silvered surface so as to form an efficient reflector for external light directed thereon. The light transmitting material 10 is molded to the inside of the reflector 9 so as to form a convex front surface 10¹.

The cylindrical side portion 9¹ of the reflector unit 9 in Fig. 2 is threaded for mounting in the face of the letters of the sign as shown in Fig. 5, and an annular rib 9² is provided in front of this threaded portion 9¹ to form a shoulder resting against the face of the letter when the reflector button is in place. The threaded portion of the reflector also serves as a grip for holding the molded light transmitting material 10 within the reflector unit 9 and is effective to diffuse light which otherwise would be reflected from this cylindrical side portion of the reflector.

A modified form of reflector button is shown in Fig. 3, which comprises a metal reflector unit 11 which is also of a general cup-shape construction similar to the reflector 9 of Fig. 2, and is filled with a molded light transmitting material 12 in the same manner as the reflector button shown in Fig. 2. This form of reflector button shown in Fig. 3, however, is not provided with a threaded cylindrical side portion, but is arranged to be pressed into snugly fitting holes in the face of the letter so that an annular rib 11¹ rests against the front surface of the letter to thereby insure perfect alignment of the reflecting surfaces of all such reflector buttons when assembled on a uniform flat surface. The concave rear portion of the reflector button in Fig. 3 is also either polished metal or silvered for

- reflecting light rays, but the inner surface of the cylindrical side 11² is roughened such as by sand blasting. This sand blasted surface of the side 11² is provided for the purpose of diffusing rays 5 of light striking the cylindrical side portion of the reflector and to provide a gripping surface for the moulded light transmitting material 12 the same as is effected by the threaded portion 8¹ of the reflector button shown in Fig. 2.
- 10 The light transmitting material 18 and 12 in Fig. 2 and Fig. 3 respectively may be glass, resin, a thermoplastic cellulose composition or any other moldable material which possesses a high light transmitting quality.
- 15 A means for applying a sign constructed in the manner described to a railway signalling system for conveying certain information to highway traffic is shown in Fig. 1. A sign S constructed in accordance with the present invention is 20 mounted on a signal pole P substantially at right angles to the direction of traffic on a highway H and may be arranged above a conventional highway crossing signal G as shown. The feature of insuring uniform alignment of the reflector 25 buttons with the face of the sign S then permits the light from an automobile or the like approaching the sign S on the highway H to be reflected substantially in the same direction from each of such reflector buttons thereby resulting in a uniform illumination of each character of the sign.

A luminous sign has thus been provided which is rendered visible at night by light reflecting buttons arranged to form the general outline of 30 the characters of the sign, and these light reflecting buttons are each rendered luminous by an external source of light reflected by a polished metal surface through an integral lens of high light transmitting quality. The present form of 35 light reflecting buttons has the advantage of being a unit structure which is unaffected by weather conditions in as much as moisture cannot enter between the reflector and the lens or light transmitting material held therein, which 40 otherwise may enter the reflector button and cause corrosion of the reflecting surface and 45 reduce the efficiency of the reflector. The arrangement for mounting the reflector buttons

in the face of the sign also permits uniform reflection of light rays from each of such reflector buttons in as much as perfect alignment of the reflecting surfaces of each is assured.

Having thus shown and described my invention, what I claim is:—

1. In a light reflecting unit, a cylindrical member closed at its inner end and open at its outer end, an inner reflecting surface on said closed end of said cylindrical member, and light transmitting material moulded within said cylindrical member and projecting from said open end thereof to form a convex outer surface.

2. In a light reflecting unit, a cylindrical member closed at the inner end and open at its outer end, an annular shoulder adjacent the open end of said cylindrical member, inner peripheral threads on said cylindrical member adjacent said annular shoulder, an inner reflecting surface on said closed end of said cylindrical member, and light transmitting material moulded within said cylindrical member to completely fill the member and threads and projecting from said open end thereof to form a convex outer surface.

3. In a light reflecting unit, a cylindrical member closed at its inner end and open at its outer end, a light reflecting medium on the inner surface of the closed end of said cylindrical member, a light diffusing surface on the inner side portion of said cylindrical member, and a light transmitting material moulded within said cylindrical member and projecting from said open end thereof.

4. In a light reflecting unit, a cylindrical member having an outwardly rounded inner end and an open outer end, an annular shoulder at the outer end of said cylindrical member, a light reflecting medium on the inner surface of the closed end of said cylindrical member, a light diffusing surface on the inner side portion of said cylindrical member, and a light transmitting material moulded within said cylindrical member and projecting from said open end thereof.

EDWARD H. BRANSON.
